UNITED STATES PATENT OFFICE

ALBERT W. WINSHIP, OF UTICA, NEW YORK, ASSIGNOR TO BERG-WINSHIP, INC., OF UTICA, NEW YORK, A CORPORATION OF NEW YORK

WARDROBE HAND CARRYING CASE

Application filed October 29, 1927. Serial No. 229,602.

My present invention relates to a hand carrying case including thereby hat boxes and suit cases and similar readily portable or hand carried baggage.

5 The purpose of my invention is to provide a hand carrying case with improved and economical means of carrying clothes suspended in an upright position when the case is carried or in other words of providing a hand carrying case within which the clothes may be suspended as in a wardrobe compartment.

10 My co-pending application for patent upon wardrobe hat box filed August 16, 1927 as Serial No. 213,410 discloses my invention broadly wherein a hat box or similar article of hand luggage is so constructed and provided with means whereby full length dresses may be supported in an upright position

15 when the case is carried by such clothes being folded once intermediate their ends over a clothes rod forming a part of the clothes rack mounted in the cover. In the construction shown in that application a relatively wide

20 flange was provided upon the cover towards its free end where the clothes rack was located so that when the case was closed the bulk of the clothes were within the flanged cover although the depending extreme ends of the garments might project into the case even

25 when the cover was raised. In the construction shown in said previous application the clothes were so permanently housed within the outline of the flanged cover by having the rod of the clothes rack either permanently

30 within the outline of the flanged cover or by having the clothes suspending rod adapted to be swung within the outline of the flanges of the cover before the cover was closed but allowing the said clothes rod to be projected outside the line of said flanges when the case was opened for convenience in access or packing.

35 In the construction shown in this application I have shown a hand carrying case either a hat box or a suit case wherein clothes may be suspended as in a wardrobe compartment by folding the garments once intermediate their ends over a clothes rod where the cover of the article of baggage has no such deep flange or in fact no flange at all except a val-

ance strip and where the clothes carrying rod is permanently supported from the free end of the cover but spaced therefrom so that the clothes rod and the bulk of the clothes are not housed within the cover but rather project 55 from the cover and into the body of the carrying case when the case is closed.

It is the purpose of this application to provide a hand carrying case with wardrobe features of the construction and type described 60 and further to provide a case of such construction, arrangement and combination of its parts as shall be convenient, practical and useful.

Further purposes and advantages of my invention will appear from the specification and claims herein.

Fig. 1 is a perspective view of an opened wardrobe hat box of a construction embodying this invention.

Fig. 2 is a vertical sectional view through such wardrobe hat box when closed and standing upright.

Fig. 3 is a perspective view of an opened suit case illustrating one application of my 75 invention.

Fig. 4 is a plan view of a man's suit laid out over the clothes rod preparatory to being placed in the suitcase.

The wardrobe hat box shown in Figs. 1 80 and 2 consists of a main case member 10 of substantially the size of the completed case and a cover 11 hinged to the back side 12 of the case 10 at or near its upper edge. The case 10 is formed of suitable material in the usual way having a front side 13 which forms the top of the case when the hat box is closed, opposite ends 14 and 15, a bottom 16 and a partition 17. The partition 17 is spaced a few inches from the back side 12 of the 85 case and parallel thereto and is of a height somewhat less than the case and forms a space or wall 18 between said partition and the back 12. In this type of wardrobe hat box the cover 11 has no deep flanges after the manner of many forms of trunks or hat boxes but has a substantially flat cover which about its three free edges is provided with narrow valance strips 19 which overlap the corresponding edges of the hat box when 90 95 100

the cover is closed to aid in strengthening the box and to provide a dust-proof and substantially water-proof joint. The inner surface, however, of this cover rests flat down upon the upper edges of the front ends and back of the case.

Very close to the free corners of the cover there are mounted on the inner side of the cover the inwardly projecting and oppositely placed brackets 20 and 21. These brackets may conveniently be formed of suitable sheet metal having base portions 22 resting flat against the inside of the cover and fastened thereto by suitable fastening members 23. The bodies of the brackets extend outward from the cover substantially at right angles thereto and support preferably in removable fashion the clothes rod 24. A convenient form of removably but non-rotatably mounting said clothes rod is to have the ends of said rods angular or D-shaped in cross section with correspondingly shaped holes in the upper ends of the brackets. The brackets are sufficiently resilient to be conveniently sprung apart for the removal or re-placement of the clothes rod, but with the brackets stiff enough to prevent accidental displacement of the rod.

The clothes rack composed of the brackets 20 and 21 and the clothes rod 24 is of such size and arrangement that the brackets project from the cover considerably beyond the free edges of the valance strips 19 so that the rod 24 is located forward of the valance strips when the cover is opened and the whole clothes rack projects for its entire extent into the main case of the hat box when the hat box is closed.

Fig. 1 shows a wardrobe hat box embodying this invention with several dresses hung over the clothes rod 24. The dresses have been folded once intermediate their length with the clothes rod located at the inside of said fold and with the opposite parts of the dresses hanging downwardly on the opposite sides of said clothes rod with the extreme ends as the waist band and hem of such dresses projecting into the well 18 of the hat box. The articles of clothing may be placed over the clothes rod with the clothes rod in place as shown in Fig. 1 or the clothes may be laid out flat in a pile and then loaded onto the rod 24 by passing the rod 24 underneath the middle of the pile and lifting the rod up. The rod so readily loaded may be placed in the open cover of the case. The depending portions of the clothes are held back against the cover by suitable straps 25 preferably having interlocking or hooking members 26 at their ends. Usually two such straps are used one close to the lower edge of the cover and one a little more than half-way up to the clothes rod. Hats or other articles may be placed in the main compartment of the case forward of the partition 17. The case

is then closed either by bringing the cover down upon the case or raising the case to the cover. Suitable locking members 27 having their co-operating parts upon the cover and the case are provided as usual upon such articles. Handle 28 is secured to the front 13 of the case.

Fig. 2 is a vertical sectional view of the said hat box when closed and standing upright.

It will be noticed that the clothes rack and the whole mass of clothes suspended out from the cover when the case is opened, are really within the main case of the hat box when the hat box is closed.

When this article of baggage is closed and stood upright the wardrobe compartment really consists of an L-shaped part with the great length of the clothes extending downwardly from the clothes rod 24 but with the lower ends of the depending clothes extending at a right angle or horizontally into the well 18. The lower clothes-retaining strap 25 is far enough up from the bottom of the cover to be just above the partition 17 and form the bend in the clothes when the hat box cover is closed. As will particularly appear from Fig. 2 the brackets 20 and 21 are as close to the top of the cover as may be and yet pass inside the front 13 of the case. Similarly the rod 24 is carried as close as possible to the top of the brackets so that the clothes rod will be very close to the top of the cover. By getting the clothes rod thus substantially into the plane of the upper edge of the cover when the cover is opened full utilization is had of the width of the cover and of the depth of the well 18 to the end that full sized dresses or other articles of clothing may be supported wardrobe fashion in a hat box by folding the clothes over the clothes rod 24.

Preferably the clothes rod 24 is covered with felt or velveteen which overcomes any tendency of the clothes to slide either way off from the rod. Usually stop straps 29 are provided having their opposite ends attached respectively to the case and to the cover so as to hold the cover in upright position a little back of the vertical plane.

Fig. 3 shows this invention applied to an ordinary suitcase and adapted as shown to carry a man's clothes suspended upright in a wardrobe compartment within the suitcase when the suitcase is closed. This is accomplished by the same means as already described in connection with the hat box and the parts are denoted by similar reference numerals with the addition of the exponent "". It will be understood that the suitcase is of the usual suitcase construction and that the cover has simply the bone narrow valance strips overlapping the upper edges of the suitcase. Notwithstanding the different proportions of the suitcase, by applying my in-

vention thereto I am enabled to hang a man's coats and trousers over the clothes rod supported upon the cover of the suitcase. In Fig. 4 there is indicated somewhat diagrammatically the arrangement of a pair of trousers and a coat with the clothes rod placed beneath said clothes and transversely thereof. By raising the rod the clothes are lifted therewith and allowed to fold themselves easily over the clothes rod whereupon they may be transferred to the suitcase by placing the clothes rod in its supporting brackets.

It will be noticed that in either form of my invention the clothes rod extends substantially the whole length of the cover since the brackets are placed as close to the side edges of the cover as may be and yet have the brackets pass down inside of the ends of the hat box or of the suitcase. In this way the clothes racks provided in these hand cases are of unusual capacity because the clothes can be arranged over the whole length of the rod. In either form of the carrying case here shown the partition 17 or 17' protects the bottom ends of the garments from any pressure or creasing by keeping the clothes or other baggage in the main compartment of the case up from the lower end of the clothes when the case is raised to carrying position.

What I claim as new and desire to secure by Letters Patent is:

1. In a hand carrying case, the combination of a box-like case, a cover hinged to the back of said case near its upper edge and a clothes rack comprising a pair of spaced brackets on the inside of said cover close to the free front edge and projecting permanently beyond said cover and a clothes rod mounted at its ends on said brackets beyond said cover and spaced from the cover but close to the plane of the free front edge of the cover whereby clothes may be supported in an upright position when the case is carried by being folded once intermediate their ends over said clothes rod with the opposite ends of the clothes projecting into the open case, and means for detachably holding the depending portion of the clothes opposite the cover towards said cover, said clothes rack and the clothes projecting beyond the cover into the case when the cover is closed.

2. In a hand carrying case, the combination of a box-like case, a cover hinged to the back of said case near its upper edge and having a narrow flange or valance strip about its sides and a clothes rack comprising a pair of spaced brackets on the inside of said cover close to the free front edge and projecting permanently beyond the cover flange or valance strip and a clothes rod mounted at its ends on said brackets beyond the said flanges or valance strip and spaced from the cover but close to the plane of the

free front edge of the cover, whereby clothes may be supported in an upright position when the case is carried by being folded once intermediate their ends over said clothes rod with the opposite ends of the clothes projecting into the open case, and means for detachably holding the depending portion of the clothes opposite the cover towards said cover, said clothes rack and most of the clothes projecting beyond the flange of the cover into the case when the cover is closed.

3. In a hand carrying case, the combination of a box-like case, a cover hinged to the back of said case near its upper edge and a clothes rack comprising a pair of spaced brackets on the inside of said cover close to the free front edge and projecting permanently beyond said cover and a removable clothes rod mounted at its ends on said brackets beyond said cover and spaced from the cover but close to the plane of the free front edge of the cover, whereby clothes may be supported in an upright position when the case is carried by being folded once intermediate their ends over said clothes rod with the opposite ends of the clothes projecting into the open case, and means for detachably holding the depending portion of the clothes opposite the cover towards said cover, said clothes rack and the clothes projecting beyond the cover into the case when the cover is closed.

4. In a hand carrying case, the combination of a box-like case, a cover hinged to the back of said case near its upper edge and a clothes rack comprising a pair of spaced brackets permanently projecting on the inside of said cover beyond said cover but close to the free front edge and a clothes rod mounted at its ends on said brackets beyond said cover and spaced from the cover but close to the plane of the free front edge of the cover, whereby clothes may be supported in an upright position when the case is carried by being folded once intermediate their ends over said clothes rod with the opposite ends of the clothes projecting into the open case and means for detachably holding the depending portion of clothes opposite the cover towards said cover, said clothes rack and the clothes projecting beyond the cover into the case when the cover is closed.

5. In a hand carrying case, the combination of a box-like case provided with a partition spaced from the back side of the case and forming a well, a cover hinged to the back of said case near its upper edge and a clothes rack comprising a pair of spaced brackets on the inside of said cover close to the free front edge and projecting beyond the recess of the cover and a clothes rod mounted at its ends on said brackets beyond said cover and spaced from the cover but

close to the plane of the free front edge of the cover whereby clothes may be supported in an upright position when the case is carried by being folded once intermediate their ends over said clothes rod with the opposite ends of the clothes projecting into the said well, and means for detachably holding the depending portion of the clothes opposite the cover towards said cover, said clothes rack and the clothes projecting beyond the cover into the case when the cover is closed and said partition protecting the lower ends of the clothes in the well from pressure from the clothes in the main compartment of the case.

In witness whereof I have affixed my signature, this 19th day of October, 1927.

ALBERT W. WINSHIP.
